UNITED STATES PATENT OFFICE.

RAY L. CARTER, OF SYRACUSE, NEW YORK, ASSIGNOR OF ONE-HALF TO LOUIS O. BUCHHOLZ, OF SYRACUSE, NEW YORK.

GAGE.

1,231,238.

Specification of Letters Patent. Patented June 26, 1917.

Application filed October 4, 1916. Serial No. 123,624.

To all whom it may concern:

Be it known that I, RAY L. CARTER, a citizen of the United States, residing at Syracuse, in the county of Onondaga and State of New York, have invented certain new and useful Improvements in Gages, of which the following is a specification.

This invention relates to improvements in gages, designed particularly for use in connection with disk-grinders and like machines.

The object of the invention is to provide a novel and simple device for mounting upon the usual work-table of disk-grinding machines, the body of the said device having perforations for centering patterns and other work to be ground. A further object is to provide means for attaching the gage to the work-table for permitting the gage to slide on the table and at the same time allowing the body of the gage to be partially rotated for adjusting and setting the body in different positions relatively to the grinding disk. A further object is to provide means for accurately determining and for maintaining the adjustments. And a further object is to provide auxiliary parts which are detachably mounted upon the flat gage body, for gaging the grinding of segments and similar parts.

I attain these objects by the means set forth in the detailed description which follows, and as illustrated in the accompanying drawing, in which—

Figure 1 is a top plan view of a disk-grinder to which my improvements are applied.

Fig. 2 is a vertical cross-section taken on line 2—2 of Fig. 1.

Fig. 3 is an enlarged top-plan view of the gage having associated therewith the auxiliary gaging parts.

Fig. 4 is a front-edge view of the same.

Figs. 5 and 6 are respectively a top-plan and a side-elevation of the auxiliary gaging part.

Fig. 7 is an enlarged view of one of the centering devices employed for positioning the work on the perforated body.

In the drawing, 2 represents generally a

disk grinder including the grinding disk 3 and the adjustable work-table 4, the said table extending horizontally across the face of the disk and having a longitudinal groove 5, all of which parts may follow the usual construction.

My invention consists of a flat plate or body 7, preferably of irregular shape as shown, having a straight edge 8 facing the disk 3, and a straight edge 8' at right angles 60 to the edge 8. The opposite edge from the portion 8 is provided with a depending lip or lug 9, which limits the movement of the body toward the disk 3. This lug is perforated and threaded to receive an adjusting screw 10, which engages the edge of the table, and the said lug is also split below the said screw, and a locking screw 11 is applied to the split end of said lug, for binding and holding the screw 10 from accidentally turning. A third screw 12 is threaded into the lug 9, the inner end of which engages the outer edge of the table 4. This latter screw is employed for adjusting the gage body 7, so that the edge 8 may be positioned exactly parallel to the plane of the disk 3. The screw 12 is not operated except when the gage is first applied to the table.

13 represents a guide bar which is pivoted to the under side of the body 7 by a screw 80 or rivet 14, the latter piercing a lateral lug or arm 7' of the body 7. The guide 13 is disposed in the slot or groove 5 of the table, and while holding the gage body 7 in place on the table, allows the said body to be 85 moved freely in the direction of said slot for adjusting the gage relatively to the center of disk 3, (see dotted lines Fig. 1). By providing the pivot 14, the body 7 may be swung readily and freely and without danger of 90 cramping on said point toward and away from the disk 3, as shown by dotted lines in Fig. 3, while the guide 13 retains its normal position in the groove 5. The rotation or movement of the body 7 away from the disk 95 3 may be regulated by the screw 10, and the angle of the edge 8 relatively to the face of the disk 3 may be gaged accurately by said screw. This feature is advantageous for grinding certain patterns or parts as well as 100

other work, where bevels or angles are required.

The plate or body 7 has several rows of perforations 15, which are preferably staggered as shown. These perforations are provided for centering different articles, as A shown in dotted lines Figs. 1 and 2, while they are being ground, and for this purpose it is customary to employ a centering-part, 10 as 16, having a cylindrical body which is disposed in the perforations 15 and which fits the holes loosely enough to allow the work to be freely rotated or manipulated during the grinding operation. Centering-part 16 has a tine or point 17 which is forced into the wood or other material, and which is preferably small in diameter so as not to disfigure or injure the pattern. The full and dotted lines in Fig. 2 show the application 20 of the centering-part 16 to a circular pattern or part A, which has been ground by contact with the disk 3. The larger the piece of work to be ground the farther the centering-part 16 is positioned from the disk 25 3. By providing a relatively large number of the holes 15 and staggering them as shown, many different centers varying only slightly in measurement may be taken care of.

In pattern-making, a large number of 30 segments, as 18, 19, and 20, shown in Fig. 3 are employed, and these must be trimmed or ground so as to be accurately fitted for forming a true circle. Usually patterns of this character are laminated or built-up, and 35 consist of three or more layers, and each layer, as a rule, comprises six segments. Heretofore, the segments have been blanked out, and the ends have been trued by what is known as a trimmer. In the present device, I provide an auxiliary set of gage-parts consisting of a pin or stud 21, which is inserted in a perforation 20' preferably located near the disk 3 or edge 8 of the body 7, and a slideable gage 22 having a slot 22' 40 through which a thumb-screw 23 is inserted and threaded into either one of a number of holes, as 24-24'-24", according to the size or arc of the segments to be ground. By providing the gage-member 22, this 45 part may be moved forwardly or backwardly and also rotated so as to bring the square end 25 into fair engagement with the segments. The tightening up of the screw 23 then holds the slide 22 in place. This 50 provision enables me to adjust the auxiliary gage for accurately grinding segments of varying curvatures or arcs without additional parts.

Having thus described my invention, 55 what I claim as new and desire to secure by Letters Patent, is—

1. In a gage for disk grinders, the combination with the work table, of a substantially flat perforated body pivotally mount-

ed upon said work table adjacent and adapted to be rotated toward and away from the grinding disk, and having a depending lug, an adjusting screw threaded in said lug, and a set screw for maintaining the adjustment of said body, the edge of the table adjacent said lug being in the path of movement of the ends of said screws and engaged thereby when the gage body is moved toward the grinding disk. 65

2. In a gage for disk grinders, the combination with the work table having a longitudinal groove, of a substantially flat perforated body having a depending lug, a guide-bar slideable in said groove, said bar pivoted to the underside of the body upon which said body is rotatable, and means carried by said lug for adjusting the body on the said guide bar. 75

3. In combination with a work table having a longitudinal groove, a gage, including a body having a plurality of perforations to receive a work-centering part, a bar upon which said body is pivoted, said bar slideable in the groove of the work table, means for adjusting said body relatively to said bar, and means for maintaining the adjustment of the said parts. 80

4. In combination with a work table having a longitudinal groove, a gage, including a substantially flat body having work-centering perforations arranged in staggered rows and having a depending lug supporting a number of adjusting screws which engage one edge of the table when said body is moved toward the grinding disk, and a guide-bar pivoted to the underside of said body upon which said body is rotatable for gaging work of different size and shape, the said bar disposed in the groove of said work table. 90

5. The combination with the work table, of a duplicating gage, including a guide-bar disposed in a groove in said work table, a body having perforations to receive work-centering parts, said body pivoted to one end of said guide-bar and resting upon said work table adapted to be rotated horizontally for gaging work of different size and shape, and means for adjusting and for maintaining the adjustment of said body relatively to said guide-bar. 100

6. In a gage for disk grinders, the combination with a grinding disk and a work table, said table having a longitudinal groove, a guide-bar disposed in said groove, a gage body pivoted to one end to said guide-bar adapted to be swung on said pivot toward and away from the grinding disk, a screw for effecting the rotation of the body in one direction, and a screw for limiting the movement of the body in the opposite direction, one edge of the table disposed in the path of the movement of the ends of 110

125

said screws and engaged thereby when the body is moved toward the grinding disk.

7. In a gage for disk grinders, the combination with the grinding disk and the work-table, of a gage body adapted to lie flat on the table, said body having a plurality of work-centering perforations, a guide upon

which said body is pivoted, said guide slidable in a groove in said table, and means for adjusting and holding said body in different angular positions relatively to the grinding disk and said guide. 10

In testimony whereof I affix my signature,

RAY L. CARTER.
